UNITED STATES PATENT OFFICE.

JOSEPH BIJUR, OF NEW YORK, N. Y., ASSIGNOR, BY MESNE ASSIGNMENTS, TO BIJUR MOTOR APPLIANCE COMPANY, A CORPORATION OF DELAWARE.

ENGINE STARTING APPARATUS.

1,307,177.

Specification of Letters Patent. Patented June 17, 1919.

Application filed June 25, 1913, Serial No. 775,670. Renewed November 23, 1918. Serial No. 263,947.

To all whom it may concern:

Be it known that I, JOSEPH BIJUR, a citizen of the United States, residing at New York, in the county of New York and State of New York, have invented certain new and useful Improvements in Engine Starting Apparatus, of which the following is a full, clear, and exact description, such as will enable others skilled in the art to which it applies to make and use the same.

This invention relates to engine-starting apparatus, and with regard to certain more specific features, to electrical means for starting internal combustion engines.

One of the objects of the present invention is to provide practical, inexpensive and durable means for setting in rotation an automobile engine or other prime mover incapable of starting itself.

Another object is to provide apparatus of the above type in which the source of power used for starting the engine is positively, effectively and completely disengaged from the engine when the latter has started, regardless of the position of the manually operated parts.

Another object is to provide starting apparatus embodying a reliable and durable automatic disengaging device whose action is wholly independent of electric currents.

Another object is to provide a compact arrangement of parts wherein centrifugal force acting upon suitably disposed masses is utilized to unmesh a gear and pinion connected respectively with the engine and the starting motor.

Another object is to provide a simple and durable starting apparatus of few parts, inexpensive to manufacture, easily assembled and efficient in action.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein are shown one or more of various possible

embodiments of the several features of the invention,

Figure 1 is a view, partly diagrammatic, of one form of starting apparatus;

Figs. 2 and 3 are views of the apparatus illustrated in Fig. 1, showing certain parts in different positions;

Figs. 4 and 5 are details of the apparatus shown in Fig. 1;

Fig. 6 is a diagram of a modified form of starting apparatus;

Figs. 7 and 8 are views of the apparatus illustrated in Fig. 6, showing certain parts in different positions;

Fig. 9 is a detail of the apparatus shown in Fig. 6;

Fig. 10 is a view, partly in section, of a third and preferred form of starting apparatus, showing the axially movable portions in two positions;

Fig. 11 is a view corresponding to Fig. 10, showing the axially movable portions in a third position;

Fig. 12 is a section on the line 12—12, Fig. 10; and

Fig. 13 is a diagram illustrating the apparatus of Fig. 10, together with a preferred arrangement of electrical connections.

Similar reference characters refer to similar parts throughout the several views of the drawings.

By way of explanation, it may be stated that the present invention is directed, in some of its more specific features, to the starting of automobile engines simply by the depression or other movement of a single hand or foot operated lever without requiring the driver to leave his seat. The need for a device of this sort, which is not only reliable and quick acting, but also inexpensive and to a certain extent automatic, has been felt for a number of years.

It is necessary, for a starting apparatus to be successful, that it be readily applicable to automobiles now in use at a minimum cost of installation and without requiring the services of a high priced mechanic or electrician.

Furthermore, the apparatus must be capable of performing its cycle of operations a considerable number of times without materially draining its source of energy,

such as a storage battery, which is necessarily of limited capacity. As the description progresses, it will be seen that these requirements have been fully met and that 5 an apparatus is provided in which the required standard of excellence has been attained.

Referring now to the drawings, and more particularly to Fig. 1, there is shown at 10 a member, such as a fly-wheel, in driving connection with the engine (not shown), to which the starting apparatus is applied. On this fly-wheel 1 is a gear 2 adapted at predetermined times to mesh with the teeth of 15 a pinion 3, the latter being feather-keyed upon the shaft 4 of an electric or other motor 5. Inasmuch as an electric motor is preferred for rotating the shaft upon which the pinion 3 is mounted, such a motor is 20 illustrated in the drawings, with its field 6 and armature 7 in series with each other and with the main switch 8. The pinion 3 is urged toward the left (in Figs. 1, 2 and 3) by the coil spring 9 and is limited in its 25 leftward longitudinal travel by the washer 10 and lock-nut 11 mounted upon the floating end of the motor shaft 4. The pinion carries, in addition to the teeth 12, a suitable number of leaf or blade springs 13, 30 bolted or otherwise secured as at 14 to the pinion 3 and provided at their opposite ends with members 15 of suitable shape and having considerable mass. Mounted also upon the pinion 3, as by the retaining bolts 16, 35 are the slotted projections 17 corresponding in number to the number of leaf springs 13 which pass respectively through the slots 18 in these projections. In the embodiment illustrated in Figs. 1, 2 and 3, the projections not only serve the purpose of limiting 40 the radial displacement of the members or "weights" 15 through the connections at the slots 18 with the leaf springs 13, but provide at the shoulders 19 suitable surfaces 45 for contacting with the washer 10, provided, as above indicated, to limit the leftward travel of the pinion 3 and its associated parts.

When the starting apparatus is not in 50 operation, the parts are located as indicated in Fig. 1, with the pinion 3 disengaged from the gear 2 and the weights 15 firmly pressed inwardly against the cylindrical extension 20 of a horizontal shaft 21 reciprocable by 55 the hand or foot operated rod 22 acting in conjunction with the spring 23 and bell-crank lever 24, the spring 23 tending, as will be obvious, to force upward the rod 22, which for convenience will be termed 60 the "pedal". From this it will be clear that the downward movement of the pedal 22 in opposition to the spring 23 will cause the counter-clockwise rotation of the bell-crank lever 24, which in turn, through the 65 pin-and-slot connection at 25, will move the

horizontal shaft 21 toward the right, and since the weights 15 are firmly pressed inwardly against the reduced extension 20 of this shaft, the movement of the shaft toward the right will cause at once an engagement of the weights 15 with the shoulder 26 and the pinion 3 will move toward the gear 2 in opposition to the force exerted by the coil spring 9, the relative proportions of blade springs 13 and coil spring 75 9 being so designed that this motion of the pinion toward the right takes place without materially distorting the leaf springs 13. If now at this time a slight amount of current be supplied to the motor in order 80 to set it in slow rotation, the pinion will turn sufficiently to insure meshing with the teeth of the gear as soon as the former has moved sufficiently far toward the right. A preferred means for supplying such a current to the motor at this time is illustrated in Fig. 1 as comprising the main switch 8 whose movable contacts 27, 28 are mounted directly on the horizontal shaft 21, above described. As indicated in Figs. 1, 2 and 85 3, a slight movement of the shaft 21 is sufficient to establish an electrical connection between the movable contact 27 and the fixed contacts 29, 30, thereby completing a circuit from the positive side of the battery 95 31 through the armature 7 and field 6 of the motor, starting resistance 32, fixed contact 29, movable contact 27 and fixed contact 30 to the negative side of the battery, and as a result the armature 7 and pinion 100 3 rotate slowly. The continued movement toward the right of the horizontal shaft 21 causes the engagement of gear 2 and pinion 3 and almost immediately thereafter the starting resistance 32 is short-circuited by 105 virtue of the connection between the movable contact 28 and fixed contacts 33, 34 of the main switch 8, as clearly illustrated in Fig. 2 of the drawings. The motor windings are now sufficiently energized to set 110 in rotation the fly-wheel 1 and the engine, and as soon as the latter begins to rotate under its own power, the centrifugal force acting upon the weights 15 becomes sufficient to move them outward in opposition 115 to the leaf springs 13 through a distance greater than the radial depth of the shoulder 26. Then the coil spring 9, having nothing to oppose its expansion, moves the pinion 3, leaf springs 13 and weights 15 120 toward the left, thereby automatically unmeshing the pinion 3 and gear 2 as soon as the engine has started, as indicated in Fig. 3. The operator will ordinarily now release the pedal 22 and the parts will come 125 to rest in the position illustrated in Fig. 1. If, however, the pressure is not removed from the pedal, the motor will rotate at its free running speed, consuming little power and having no effect whatever upon the 130

engine, since the pinion can not be re-meshed with the gear while the pedal is depressed. Then when the pedal 22 is allowed to rise, the motor comes to rest with the parts as shown in Fig. 1.

In order to prevent the downward movement of the pedal when the engine is rotating, a suitable interlock 35 may be provided, this mechanism comprising, in the present instance, a voltage coil 36 (Figs. 1, 2, 3 and 5) connected across the terminals of the generator 37 driven by the engine, this coil, when energized, attracting in opposition to the spring 38 the armatures 39, 40, secured respectively to the two halves 41, 42 of a split collar, thereby bringing the two hinged members of this collar into the annular groove 43 of the pedal 22, the groove and collar registering when the pedal is in its normal position of rest, indicated in Fig. 1. It will be obvious, without further elaboration, that as long as the voltage coil 36 is energized, it is impossible to depress the pedal 22 so that energy can not be supplied to the motor 5 until the engine has come to rest.

In the several figures of the drawings where the generator 37 is illustrated, an automatic switch is shown, more or less conventionally, as comprising a current coil 44 and a voltage coil 45 wound so as to assist the current coil in maintaining a closed circuit at the contacts 46, the switch being opened by reverse current through the current coil and closed whenever the voltage coil is sufficiently energized. The generator is illustrated for convenience as a shunt-wound machine without a voltage or current regulator, it being understood, of course, that a suitable regulator is in practice provided and that the present invention is applicable to any suitable type of generator, regulator and automatic switch.

In Figs. 6, 7 and 8 is illustrated another embodiment of the present invention. As before, a pedal 22 is provided together with a spring 23, bell-crank lever 24, interlock 35, main switch 8, fly-wheel 1, gear 2, motor 5 and reciprocable pinion 3 feather-keyed on the motor shaft 4. In the present modification the pinion is moved toward the left, out of engagement with the gear, either by releasing the pressure on the pedal 22 and allowing the spring 23 to rotate the bell-crank lever 24 clockwise or by the outward movement of the weights 47 secured, as indicated, to the pinion 3 and collar 48 by the pivoted links 49 preferably integral therewith. When the engine is to be started the pedal 22 is depressed, thereby moving toward the right the horizontal shaft 50, collar 48 and switch rod 51. One or more of the weights 47 may at this time tend to buckle outward, but even if both the weights should buckle outward, the collar

48 coming soon into engagement with the left end of the coil spring 52 would, through this comparatively stiff spring, effect the movement of the pinion 3 toward the gear 2. As before, connection is made at the auxiliary contacts 29, 27, 30 of the main switch 8 to set the motor in slow rotation prior to engagement, and, as soon as engagement is completed, the closing of the circuit at the main contacts 33, 28, 34 energizes the motor sufficiently to enable it to start the engine. As soon as the engine has started to rotate under its own power, the increased angular velocity of the weights 47 causes them to fly outward and thereby disengage the pinion 3 from the gear 2 even though the pedal 22 remains depressed. Premature reengagement is prevented by the continued rotation, at high speed, of the weights 47 as long as the pedal is depressed, since the upward movement of the pedal by deenergizing the motor only after connection is broken at the auxiliary contacts 29, 27, 30 insures the continued rotation, at high speed, of the weights until the collar 48 has almost reached the end of its leftward travel. While the engine is in rotation the interlock 35 prevents the downward movement of the pedal.

A third, and preferred, embodiment of the invention is illustrated in Figs. 10 to 13, inclusive. The motor 5, fly-wheel 1, gear 2 thereon, pinion 3 on the floating end of the motor shaft 4, the generator 37, automatic switch 46 and main switch 8 are provided, as in Figs. 1 to 9, and the pedal 22, electro-magnetic interlock 35 and bell-crank lever 24 serve, as in the previous figures, to illustrate a suitable way of operating the main switch 8 and other parts of the mechanism. In the present embodiment of the invention the pinion 3 is feather-keyed, as before, upon the shaft 4 of the motor, but the spring 53 tending to throw this pinion out of mesh with the gear 2 is mounted within the motor shaft instead of around the same, as in Fig. 1. The two arrangements of spring are, for the purpose of the present invention, interchangeable. The face-plate 54 secured, as by the screws 55 to the outer end of the pinion member 3, serves to retain on said member the annular member 56 feather-keyed as at 57 upon the pinion member 3 and comprising parallel flange portions 58, 59 suitably secured together, as at 60, in such a way as to exclude dust, and carrying between them the weighted levers 61 pivoted, as at 62, to trunnions mounted in the two flange members 58, 59. These weighted levers, as illustrated more in detail in Fig. 12, are fastened together at their free ends by a coil spring 63, against the retractile force of which the weighted levers move radially outward to an extent proportional to their 130

speed of rotation. When the weights are at rest, or rotating below a predetermined speed, the inwardly projecting lugs 64 thereon press inwardly against the outer 5 surface of the pinion member 3, and if the annular member 56 is in the position illustrated in Fig. 10 these lugs register with and project into an annular groove 65 provided for that purpose in said pinion member. At 10 one end of the annular member 56, preferably the inner end, there is provided an annular groove 66 into which the bifurcated portion 67 of an operating rod 68 is adapted to fit, this rod being moved in a direction 15 parallel to the axis of the motor shaft 4 by suitable mechanical connections, as at 69, 24, with the pedal 22.

Assuming now that the engine is to be started, the pedal 22 is depressed, as in the 20 embodiments heretofore described, with the result that first the auxiliary contacts 27, 29, 30 of the main switch are closed, thereby setting the motor 5 in slow rotation; second, the bifurcated operating lever 68 moves the 25 annular member 56, and through the lugs 64 thereof, the pinion member 3, toward the right from its dotted-line position in Fig. 10 a sufficient distance so that the slowly rotating pinion comes into mesh with the stationary teeth 2 of the fly-wheel; third, the continued downward motion of the pedal closes the main contacts 28, 33, 34 of the main switch 8 at the time the pinion 3 has come 30 completely into mesh with the gear 2, as illustrated in solid lines in Fig. 10. The motor is now energized sufficiently to enable it to set the engine shaft in rotation through pinion 3 and gear 2, and as soon as the engine begins to rotate under its own power 35 40 the outward movement of the weighted levers 61 causes the inwardly projecting lugs 64 thereof to pass out of the annular groove 65 on the pinion member 3. This removes the only obstacle to the leftward movement 45 of the pinion member under the influence of the coil spring 53 within the motor shaft. The pinion member therefore promptly slides toward the left, out of engagement with the gear 2 of the fly-wheel, as illustrated in Fig. 11, the axial travel of the pinion member being limited by the length of the slot 70 thereof in co-operative relation of the pin 71 on the motor shaft. This disengagement of gear and pinion, it is noted, is 50 wholly independent of the position of the pedal 22 and bell-crank 24. After disengagement has occurred, if the pedal be still depressed the motor will rotate at its free running speed, which should, of course, be 55 low enough for safety, as a no-current release might otherwise need to be added to the apparatus. When pressure on the pedal is released the retractile spring 23 restores the bell-crank lever 24, main switch 8 and 60 bifurcated operating rod 68 to their initial

positions, thereby disconnecting the motor from the source of power and moving the annular member toward the left into the position illustrated in dotted lines in Fig. 10, whereupon the inwardly projecting lugs 64 70 on the weighted levers 61 register with and enter the annular slot 65 in the pinion member 3, due to the retractile force of the coil spring 63. The electro-magnetic interlock 35 serves as before, to lock the pedal 22 in its 75 raised position whenever the engine is running.

It will be apparent from the drawings that with this embodiment of the invention a combination of elements especially adapted for engine-starting is provided within a small compass at a minimum cost.

Briefly stated, the operation of the embodiment illustrated in Figs. 1, 2 and 3 is as follows:—When the engine is to be started, 85 the pedal 22 is depressed, thereby slowly rotating the motor while the pinion 3 is moyed toward the gear and then sending a heavy current through the motor as soon as engagement between gear and pinion has been 90 effected. When the engine has started, the high speed of rotation of the weights 15 causes them to slide outward over the end of the shoulder 26, whereupon the coil spring 9 causes the pinion 3 to move toward the left, 95 out of engagement with the gear 2. Then as soon as pressure is released from the pedal the motor comes to rest. The electro-magnetic interlock 35 connected across the terminals of the generator 37 locks the pedal 100 in its raised position and prevents the engagement of gear and pinion when the engine is rotating. In Figs. 6, 7 and 8 disengagement is effected by the outward movement of the weighted links 49 connected respectively to a pedal-controlled member 48 and to the pinion 3. When the pinion is moved into engagement with the gear, the coil spring 52 transmits power from the member 48 to the pinion 3 in case all the 105 weighted links 49 should buckle. In Figs. 10 to 13 the weighted levers 61 are provided with inwardly projecting lugs 64 which, at a predetermined speed of rotation, pass out of the annular groove 66 on the pinion member 3 and permit the latter to be disengaged from the gear 2 through the force exerted by the expansile spring 53 within the motor shaft. In all the figures the movement of the pinion toward the gear, as well as the 110 operation of the starting switch, is accomplished directly through the single hand or foot operated rod 22.

It will thus be seen that there is provided apparatus in which the objects enumerated 115 are achieved and other advantageous ends attained.

In the above description certain expressions, such as "left", "right", "clockwise" and "counterclockwise", have been used to 120

designate simply the relative locations and relative movements of coöperating parts, and it will be obvious that these words are neither used in an absolute sense nor intended in any way to illustrate the arrangement of the specific expressions employed.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:—

1. In a motor vehicle, the combination with an internal combustion engine, an electric starting motor therefor, movable connecting means for said motor and engine, a source of current and connections for operating said motor, and means including a single actuating member for operating on said connections to start the motor and for moving said connecting means into operation and afterward operating on said connections to give the motor a working energy for starting the engine.

2. In a motor vehicle, the combination with an internal combustion engine, an electric starting motor, a battery circuit for said motor including a resistance and movable connecting means for said motor and engine, of means including a single actuating member for closing said circuit with the resistance in, then moving said connecting means into operation and then cutting said resistance out of said circuit *seriatim*.

3. In a motor vehicle, the combination with an internal combustion engine having a gear mounted thereon, of an electric starting motor, a battery, a pinion adapted to be driven from said motor and normally out of mesh with said gear, manually controlled means adapted to move said pinion into mesh with said gear, connecting means adapted to connect said battery with said motor with reduced driving power, connecting means adapted to connect said battery with said motor with substantially full driving power, and a connection between said manually controlled means and both of said connecting means whereby the first of said connecting means is rendered operative prior to meshing of said pinion with said gear and the second of said connecting means is rendered operative after said meshing occurs.

4. In a motor vehicle, the combination with an internal combustion engine having a gear mounted thereon, of an electric starting motor, a battery, a pinion adapted to be driven from said motor and normally out of mesh with said gear, manually controlled

means adapted to move said pinion into mesh with said gear, connecting means adapted to connect said battery with said motor with reduced driving power, connecting means adapted to connect said battery with said motor with substantially full driving power, and a connection between said manually controlled means and both of said connecting means whereby the first of said connecting means is rendered operative prior to meshing of said pinion with said gear and the second of said connecting means is rendered operative after said meshing occurs, said first connecting means being shaped and adapted to maintain connection until said second connecting means is operative.

5. In a motor vehicle, the combination with an internal combustion engine, of a gear driven from said engine, an electric starting motor, a pinion driven from said motor, a battery, means adapted upon actuation to connect said motor with said battery first with low driving power and thereafter with a higher driving power, and manually-controlled means operatively related to said connecting means and adapted upon actuation to operate the same and cause the meshing of said pinion with said gear after the motor is started with low driving power and before the higher driving power is applied.

6. In a motor vehicle, the combination with an internal combustion engine, of an electric starting motor, a gear driven from said engine, a pinion driven from said motor, a battery, a motor-starting device adapted upon actuation first to connect said battery with said motor with reduced driving power and thereafter, while said connection is maintained, to connect said battery with said motor with substantially full driving power, and a single manually controlled means adapted upon actuation to move said pinion into engagement with said gear, said last means being mechanically connected with said starting device and adapted to actuate the same to make said first connection prior to meshing of said pinion with said gear and said second connection subsequent thereto.

7. In engine starting apparatus for motor vehicles, in combination, an electric starting motor, a shaft driven thereby, an engine-driven gear, means comprising a pinion adapted to transmit power to said gear, means adapted to move said pinion along said shaft into mesh with said gear, and a device interposed between said power-transmitting means and said second means, tending to prevent movement of said pinion relative to said second means in a direction toward said gear while the engine is running.

8. In engine starting apparatus for motor vehicles, in combination, an electric starting motor, a shaft driven thereby, an engine

- driven gear, means comprising a pinion adapted to transmit power to said gear, means adapted to move said pinion along said shaft into mesh with said gear, and a 5 device interposed between said pinion-moving means and said power-transmitting means, mounted upon one of the same and adapted to exert yielding pressure upon the other and to tend to hold said pinion against 10 travel relative to said pinion-moving means in a direction toward said gear while the engine is running.
9. In engine starting apparatus for motor vehicles, in combination, an electric starting 15 motor, a shaft driven thereby, an engine-driven gear, means comprising a pinion adapted to transmit power to said gear, means adapted to move said pinion along said shaft into mesh with said gear, and a 20 device interposed between said pinion-moving means and said power-transmitting means, mounted upon one of the same and adapted to exert yielding pressure upon the other and to tend to hold said pinion against 25 travel relative to said pinion-moving means in a direction toward said gear while the engine is running, said device comprising a movable member and a spring urging said movable member into engaging position.
- 30 10. In engine-starting apparatus for motor vehicles, in combination, an electric starting motor, a shaft driven thereby, an engine-driven gear, means comprising a pinion adapted to transmit power to said gear, 35 means adapted to move said pinion along said shaft into mesh with said gear, and a device interposed between said pinion-moving means and said power-transmitting means, mounted upon one of the same and 40 yieldingly engaging an annular groove formed in the other and tending to hold said pinion against travel relative to said pinion-moving means in a direction toward said gear.
- 45 11. In engine starting apparatus for motor vehicles, in combination, an electric starting motor, a shaft driven thereby, an engine-driven gear, means comprising a pinion adapted to transmit power to said 50 gear, means adapted to move said pinion along said shaft into mesh with said gear, and a device interposed between said last-mentioned means and said power-transmitting means comprising a movable member mounted upon one of the same and a 55 spring yieldingly urging said member into an annular groove formed in the other and tending to hold said parts against relative longitudinal movement.
- 60 12. In engine starting apparatus for motor vehicles, in combination, an electric starting motor, a shaft driven from said motor, a flywheel gear adapted to be driven by an internal combustion engine, a sleeve 65 member on said shaft connected to be driven

thereby, an outer member mounted upon said sleeve member, teeth formed on one of said members adapted to mesh with said gear, means upon the other of said members adapted to move said teeth into meshing position, and resilient means on one of said members engaging the other of said members and tending to oppose relative movement.

13. In engine starting apparatus for 75 motor vehicles, in combination, an electric starting motor, a shaft driven from said motor, a flywheel gear adapted to be driven by an internal combustion engine, a sleeve member on said shaft connected to be driven 80 thereby, an outer member mounted upon said sleeve member, teeth formed on one of said members adapted to mesh with said gear, means upon the other of said members adapted to move said teeth into meshing position, and resilient means on one of said members engaging the other of said members and tending to oppose relative movement, said resilient means comprising 85 a movable part and a spring urging said 90 part into an annular groove.

14. In engine starting apparatus for motor vehicles, in combination, an electric starting motor, a gear adapted to be driven by an internal combustion engine, a shaft 95 driven from said motor, a sleeve mounted upon said shaft and provided with a pinion adapted to mesh with said gear, and means adapted automatically to cause said pinion to move out of mesh upon said engine being started, said sleeve fitted about said shaft substantially throughout its length outside the motor.

15. In engine starting apparatus for motor vehicles, in combination, an electric 105 starting motor, a gear adapted to be driven by an internal combustion engine, a shaft driven from said motor, a sleeve mounted upon said shaft and provided with a pinion adapted to mesh with said gear, a spring 110 tending to urge said sleeve with said pinion longitudinally out of mesh with said gear, and a mechanical centrifugal device holding said parts against said unmeshing movement until a predetermined speed has 115 thrown the parts out of holding position.

16. In engine starting apparatus for motor vehicles, in combination, an electric starting motor, a gear adapted to be driven from an internal combustion engine, a pinion driven from said motor, and speed-controlled means adapted upon said pinion being meshed, automatically to cause demeshing thereof, said means comprising a centrifugal device having locking parts 120 which swing centrifugally in a plane transverse to the shaft of said motor.

17. In engine starting apparatus for motor vehicles, in combination, an electric starting motor, a gear adapted to be driven 125

- from an internal combustion engine, a shaft driven from said motor, a sleeve upon said shaft, a pinion upon said sleeve, actuating means adapted to move said sleeve to cause 5 said pinion to move into mesh with said gear, a spring tending to move said sleeve in the opposite direction and throw said pinion out of mesh, and a centrifugal device mounted on said sleeve comprising a spring-pressed part tending to hold said actuating 10 means and said sleeve together.
18. In engine starting apparatus for motor vehicles, in combination, an electric starting motor, a gear adapted to be driven 15 from an internal combustion engine, a shaft driven from said motor, a sleeve upon said shaft, a pinion upon said sleeve, actuating means adapted to move said sleeve to cause said pinion to move into mesh with said gear, 20 a spring tending to move said sleeve in the opposite direction and throw said pinion out of mesh, a centrifugal device mounted on said sleeve comprising a spring-pressed part tending to hold said actuating means and 25 said sleeve together, said spring-pressed part being mounted to swing transversely of said shaft, and a casing inclosing said centrifugal device.
19. In engine starting apparatus for motor vehicles, in combination, an electric starting motor, a shaft driven from said motor, a flywheel gear adapted to be driven from an internal combustion engine, a sleeve member 30 on said shaft and fitted about the same for the major portion of its length and connected to be driven by said shaft, an outer member mounted on said sleeve member, teeth carried by one of said members adapted to mesh with said gear, and means 35 on the other of said members adapted to move said teeth into meshing position.
20. In engine starting apparatus for motor vehicles, in combination, an electric starting motor, a shaft driven from said motor, a flywheel gear adapted to be driven from an internal combustion engine, a sleeve member 40 on said shaft and fitted about the same for the major portion of its length and connected to be driven by said shaft, said sleeve extending toward said motor from the point at which it is driven from said shaft, an outer member mounted on said sleeve member, teeth carried by one of said members adapted to mesh with said gear, means 45 on the other of said members adapted to move said teeth into meshing position, said sleeve member being mounted to permit movement relative to said shaft, and means adapted to limit said movement.
21. In engine starting apparatus for motor vehicles, in combination, an electric starting motor, a shaft driven from said motor, a flywheel gear adapted to be driven from an internal combustion engine, a sleeve 50 member on said shaft and fitted about the same for the major portion of its length and connected to be driven by said shaft, an outer member mounted on said sleeve member, teeth carried by one of said members adapted to mesh with said gear, means on the other of said members adapted to move said teeth into meshing position, said sleeve member being mounted to permit movement relative to said shaft, and means adapted to limit said movement.
22. In engine starting apparatus for motor vehicles, in combination, an electric starting motor, a shaft driven from said motor, a flywheel gear adapted to be driven from an internal combustion engine, a sleeve 55 member on said shaft and fitted about the same for a substantial portion of its length and connected to be driven by said shaft, an outer member mounted on said sleeve member, teeth carried by one of said members adapted to mesh with said gear, means on the other of said members adapted to move said teeth into meshing position and automatically to move out of mesh on said engine being started, said sleeve and shaft being mounted to permit relative longitudinal movement, a spring resisting such movement.
23. In engine starting apparatus for motor vehicles, in combination, an electric starting motor, a gear adapted to be driven 60 from an internal combustion engine, a shaft forming an extension of and in alinement with the armature shaft of said motor, a sleeve mounted upon and fitted about said shaft for the major portion of its length, a pinion on said sleeve to be driven thereby and normally out of mesh with said gear positioned to move toward and adjacent to said motor into mesh with said gear, and means 65 driving said sleeve from said shaft.
24. In engine starting apparatus for motor vehicles, in combination, an electric starting motor, a gear adapted to be driven from an internal combustion engine, a shaft 70 forming an extension of and in alinement with the armature shaft of said motor, a sleeve mounted upon and fitted about said shaft for the major portion of its length, a pinion on said sleeve to be driven thereby and normally out of mesh with said gear positioned to move toward and adjacent to said motor into mesh with said gear, and means driving said sleeve from said shaft, 75 said last means being spaced from said pinion in a direction away from said motor.
25. In engine starting apparatus for motor vehicles, in combination, an electric starting motor, a gear adapted to be driven from an internal combustion engine, a shaft 80 forming an extension of and in alinement with the armature shaft of said motor, a sleeve mounted upon and fitted about said shaft for the major portion of its length and entirely carried by said shaft, a pinion 85

- on said sleeve to be driven thereby and normally out of mesh with said gear positioned to move toward and adjacent to said motor into mesh with said gear, means driving 5 said sleeve from said shaft, and a coil spring having its axis substantially parallel to said shaft and mounted to resist longitudinal relative movement of said sleeve and said shaft.
- 10 26. In engine starting apparatus for motor vehicles, in combination, an electric starting motor, a gear adapted to be driven from an internal combustion engine, a shaft forming an extension of and in alinement 15 with the armature shaft of said motor, a sleeve mounted upon and fitted about said shaft for the major portion of its length and entirely carried by said shaft, a pinion on said sleeve to be driven thereby and normally out of mesh with said gear positioned to move toward and adjacent to said motor into mesh with said gear, means driving 20 said sleeve from said shaft, said last means being spaced from said pinion in a direction 25 away from said motor, and a coil spring having its axis alined with said shaft, mounted to resist relative longitudinal movement of said sleeve and said shaft.
27. In engine starting apparatus for motor vehicles, in combination, an electric starting motor, a gear adapted to be driven from an internal combustion engine, a shaft forming an extension of the armature shaft of said motor, a sleeve mounted upon and 30 fitted about said shaft for a substantial portion of its length, a pinion upon said sleeve to be driven thereby and normally out of mesh with said gear and adapted to mesh therewith, and means adapted to move said 35 pinion automatically out of mesh therewith upon said engine being started.
28. In engine starting apparatus for motor vehicles, in combination, an electric starting motor, a gear adapted to be driven from an internal combustion engine, a shaft forming an extension of the armature shaft of said motor for a substantial portion of 40 its length, a sleeve mounted upon and fitted about said shaft, a pinion upon said sleeve to be driven thereby and normally out of mesh with said gear and adapted to mesh therewith, and speed - controlled means 45 adapted to move said pinion out of mesh with said gear upon said engine being started and said pinion being driven thereby at high speed.
29. In engine starting apparatus for motor vehicles, in combination, an electric starting motor, a gear adapted to be driven from an internal combustion engine, a shaft forming an extension of the armature shaft of said motor, a sleeve mounted upon and 50 fitted about said shaft substantially throughout its length, a pinion upon said sleeve to be driven thereby and normally out of mesh 55 with said gear, means adapted to move said pinion into mesh with said gear, and a spring mounted to resist relative movement between said sleeve and said shaft.
30. In engine starting apparatus for motor vehicles, in combination, an electric starting motor, a shaft driven from said motor, said shaft extending from said motor and being supported thereby, a flywheel gear adapted to be driven from an internal combustion engine, a sleeve member on said shaft and extending along the same for the major portion of its length and connected to be driven by said shaft, an outer member mounted on said sleeve member, teeth carried by one of said members adapted to mesh with said gear, and means on the other of said members adapted to cause said teeth to move into meshing position, said sleeve member being mounted to permit movement relative to said shaft, and said teeth being mounted to move into mesh toward and adjacent to said motor.
31. In engine starting apparatus for motor vehicles, in combination, an electric starting motor, a shaft driven from said motor, a flywheel gear adapted to be driven from an internal combustion engine, a sleeve member on said shaft and fitted about the same for a substantial portion of its length and connected to be driven by said shaft, an outer member mounted on said sleeve member, teeth formed on one of said members adapted to mesh with said gear, and means on the other of said members adapted to move said teeth into meshing position, said last means being affected by speed to cause unmeshing of said pinion automatically upon said engine being started.
32. In engine starting apparatus for motor vehicles, in combination, an electric starting motor, a gear adapted to be driven from an internal combustion engine, a shaft forming an extension of and in alinement with the armature shaft of said motor and supported thereby, a sleeve mounted upon and fitted about said shaft for a substantial portion of its length, a pinion on said sleeve to be driven thereby and normally out of mesh with said gear positioned to move toward and adjacent to said motor into mesh with said gear, means driving said sleeve from said shaft at a point on the side of said pinion remote from said motor, and means adapted automatically to move said pinion out of mesh therewith upon said engine being started.
33. In engine starting apparatus for motor vehicles, in combination, an electric starting motor, a gear adapted to be driven from an internal combustion engine, a shaft forming an extension of and in alinement with the armature shaft of said motor and supported thereby, a sleeve mounted upon and extending along said shaft for a substantial

portion of its length, a pinion on said sleeve to be driven thereby and normally out of mesh with said gear positioned to move toward said motor into mesh with said gear, 5 means driving said sleeve from said shaft, said last means being spaced from said pinion in a direction away from said motor, a coil spring having its axis alined with said shaft, mounted to resist relative longitudinal movement of said sleeve and said shaft, and means adapted to move said pinion automatically out of mesh with said gear upon 10 said engine being started.

34. Apparatus of the character described 15 comprising, in combination, an engine, a member driven thereby, a motor, a member driven thereby, means for engaging said members, means for rotating said motor slowly prior to engagement, means for energizing said motor strongly as soon as engagement 20 has been effected, centrifugal means adapted to disengage said members when

the engine has started, and means adapted to prevent engagement between said members when said engine is rotated. 25

35. Apparatus of the character described comprising, in combination, an engine, a member driven thereby, a source of power, a member driven thereby, means for effecting the engagement of said members and simultaneously operating said source of power, means comprising centrifugal weights adapted to disengage said members when the engine has started, a generator driven by said engine, and means affected by current generated by said generator adapted to prevent engagement between said members. 30 35

In testimony whereof I affix my signature, in the presence of two witnesses.

JOSEPH BIJUR.
